LOCK FOR PNEUMATIC THREAD REMOVERS

Richard G. Turner, Worcester, Mass., assignor to
Crompton & Knowles Loom Works, Worcester,
Mass., a corporation of Massachusetts

Application May 28, 1949, Serial No. 96,084

9 Claims. (Cl. 139—256)

1

This invention relates to pneumatic thread removers for weft replenishing looms and it is the general object of the invention to provide a simple form of lock which will temporarily hold the thread remover in thread pick-up position.

Heretofore I have proposed a pneumatic thread remover comprising a tube formed with a thread intake mouth to receive the thread of the outgoing bobbin incident to a weft replenishing operation. The tube is normally in raised position and is lowered to thread pick-up position by the transerrer arm as the latter descends when pushing a reverse bobbin into the depleted shuttle. Thread removers of this type are customarily made with a form of friction means intended to hold the remover in either its raised or its lowered position, but experience shows that after considerable use the friction means is likely to fail in its holding function and permits the remover to rebound after being moved to its pick-up position. If the remover rebounds sufficiently to elevate the thread pick-up lip behind the mouth above the thread the latter will pass under the remover without being attracted by the latter during backward motion of the lay.

It is an important object of the present invention to provide a simple lock means which will temporarily hold the thread remover in its pick-up position. This lock acts automatically as the thread remover and its carrier is rocked by the transerrer arm and holds the remover so that the lip thereon will extend to a position below the level of the thread of the depleted bobbin in the shuttle.

It is customary to provide means for resetting the remover as the lay approaches its back center position immediately following bobbin transfer. This resetting is ordinarily accomplished by a vertically reciprocating rod operated by the lay and rising as the lay moves rearwardly. It is a further object of the invention to provide means by which the resetter moves the lock to unlocked position before the resetter engages the remover carrier to return the latter to its normal raised position.

The aforesaid resetter has a rising motion for each beat-up of the lay and in order to prevent it from repeatedly engaging the lock it is a still further object of the invention to provide a positioner which may be in the form of a cam which operates to move the lock out of the range of movement of the resetter as the latter nears the upward limit of its motion during the first backward motion of the lay subsequent to bobbin transfer.

With these and other objects in view which will

2

appear as the description proceeds, the invention resides in the combination and arrangement of parts hereinafter described and set forth.

In the accompanying drawings, wherein two forms of the invention are set forth,

Fig. 1 is a side elevation of part of a weft replenishing loom having the preferred form of the invention applied thereto, the shuttle box and lay being shown in cross section and the thread remover being shown in its normal raised or idle position,

Fig. 2 is a view similar to a part of Fig. 1 but showing the thread remover in its operating or thread pick-up position,

Fig. 3 is an enlarged horizontal detailed section on line 3—3, Fig. 1, showing details of the preferred form of lock,

Fig. 4 is an enlarged vertical section on line 4—4, Fig. 1, showing the carrier for the thread remover in normal raised position with the lock in unlocked position and indicating the resetter in low position in full lines and in raised position in dotted lines,

Fig. 5 is an enlarged vertical section on line 5—5, Fig. 2, showing the remover carrier in thread pick-up position and the lock in locking position,

Fig. 6 is a view similar to a part of Fig. 1 but showing the modified form of lock, the thread remover being in its normal inactive position,

Fig. 7 is a view similar to a part of Fig. 6 showing the carrier for the thread remover in thread pick-up position and indicating the modified form of lock in locking position, and

Fig. 8 is a detail plan view looking in the direction of arrow 8, Fig. 6.

Referring to Fig. 1, the loom frame 10 has mounted thereon a support 11 for a magazine M. The latter may be of the rocking type and is mounted for angular movement on a stud 12 secured to the support 11. The latter has mounted thereon the usual transerrer stud 13 on which the transerrer arm 14 is pivotally mounted. Arm 14 has secured thereto a laterally extending depressing pin or stud 15 which over-

hangs an arm 16 of a remover carrier designated generally at 17. The latter is mounted on the stud 13 for pivotal movement therearound and is normally held in any position to which it is moved by a friction means designated generally at 18. This means may include a spring 19 and a nut 20 to tighten the spring and force a disk 21 of the friction means against part of the carrier 17.

The carrier member 17 may be made of sheet metal and has struck from the lower part thereof

front and back ears 25 and 26 in which is slidably mounted a rod 27 having secured thereto a collar 28 normally held against the rear ear 26 by a compression spring 29 surrounding that part of the rod between the front ear 25 and the collar. The effect of the spring is to hold the rod 27 in rear position but permit it to yield forwardly.

A thread remover R comprises a tube 30 having an intake mouth 31 and a depending lip 32 behind the mouth. A thread deflecting wing 33 is secured to and extends forwardly from the tube 30 and is fixed to the rear end of rod 27. A hose or flexible pipe 34 is connected to the upper end of tube 30 and leads to a source of sub-atmospheric pressures which during loom operation causes an inrush of air into the intake mouth 31.

A resetting rod or member 40 operated in known manner rises as the lay 41 moves rearwardly and descends as the lay 41 moves forwardly. The upper end of this rod is positioned to engage a lifting lug or shelf 42 on carrier 17 for the purpose of returning the carrier and remover R to normal idle position.

In the operation of the mechanism thus far described the remover R and its carrier will be in the normal raised or idle position shown in Fig. 1 with the intake mouth 31 and the tube 30 above the path of the shuttle S as the latter moves into the shuttle box 45 on the lay. At the time of transfer a reserve bobbin (not shown) from the magazine is pushed into the shuttle by the transfer arm as the latter descends, and pin or stud 45 engages arm 16 to rock the carrier and remover to the operating or thread pick-up position shown in Fig. 2. At this time the resetter rod 40 is in down position so that it does not interfere with downward motion of the shelf 42. The thread of the depleted bobbin extends across the race plate 46 of the lay and preferably over a body 47 of deformable material such as pile fabric, and as the lay moves rearwardly subsequent to weft replenishing the thread is guided by the lip 32 into or toward the mouth 31, whereupon part at least of the thread is drawn into the remover R. As the lay approaches its back center position next following bobbin transfer the resetter rod 40 returns the remover R and carrier 17 to their normal position.

The matter thus far described is of common construction and may be made and operated in known manner.

In the preferred form of the invention shown more particularly in Figs. 1 to 5, a stationary part 50 of the loom, such as a plate under the support 11, has secured thereto a stud 51 on which is pivoted a lock member 52. The stud has a head 53 and is surrounded by a torsion spring 54, the effect of which is to cause the lock member to turn in a counter-clockwise direction as viewed in Fig. 4. The lock 52 has a release element or finger 55 for cooperation with a release arm 56 secured to the resetter 40. The upper part of the lock is provided with a locking finger or latch 57 which moves over a part 58 of the carrier 17 for the purpose of locking the latter in down position. The part 58 may be formed with a control or positioning cam 59 normally engaging the latch 57.

Under normal conditions the lock and control cam 59 are in the position shown in Fig. 4, the carrier being in its raised or idle position, and the latch 57 being moved to the right so that the finger 55 is out of the path of the vertically and

regularly reciprocating release arm 56. While the parts are in this position the resetter will rise and fall once for each beat of the loom without engaging the lock member. When a bobbin transfer operation occurs the stud 13 engages the arm 16 and rocks the carrier member 17 as already described to lower the remover R, whereupon the latch arm 57, acted upon by spring 54, moves to the left as viewed in Fig. 4 over the part 58 to the locking position shown in Fig. 5. As already stated this lowering of the carrier occurs when the resetter rod 40 is in low position so that the arm 56 will not interfere with movement of the finger 55. The lock member 52 holds the remover in down position so that the lip 32 will extend below the top of the race plate 46 to be under the thread of the depleted bobbin as the lay moves rearwardly.

When the resetter 40 next rises its release arm 56 engages the finger 55 and rocks the lock 52 in a clockwise direction as viewed in Fig. 5 to a releasing position while the top of rod 40 is below the lifting lug 42. As the resetter continues to rise it rocks the carrier member 17 back to its normal position, thereby lifting the cam 59 and causing it to rock the lock until the finger 55 is out of the path of the release arm 56. The friction means 21 then holds the carrier 17 and remover R in its raised position.

In the modified form of the invention, a lock 65 is provided for engagement with the lifting lug 42. A small stand 66 secured to the support 11 is provided with a stud 67 on which the lock 65 is pivoted. A torsion spring 68 shown in Fig. 8 acts on the lock in such manner as to tend to turn it in a clockwise direction as viewed in Fig. 6. This lock has a detent 70 and a cam surface 71 above the detent, and also has a release surface or element 72 which is inclined downwardly and forwardly, as will be seen in Figs. 6 and 7. This latter surface is adapted for engagement with the top of the resetter rod 40.

Under normal conditions the modified form of lock will be as shown in Fig. 6 with the lifting lug 42 in engagement with the cam 71 so that the release element 72 is out of the path of the vertically reciprocating resetter rod 40. When the carrier 17 moves to the thread pick-up position thereof as already described in connection with the preferred form of the invention spring 68 moves the lock 65 in a clockwise direction from the position shown in Fig. 6 to that shown in Fig. 7 so that the detent 70 lies over the lug 42 to hold the remover R in down position with the lip 32 below the level of the thread of the outgoing bobbin. At this time rod 40 will be down, and as it rises its first effect is to engage the release element 72 and rock the lock 65 in a counter-clockwise direction as viewed in Fig. 7; thereby, moving the detent 70 to the right to unlock the lug 42. As rod 40 continues to rise it engages the lug 42 and returns the carrier 17 to its normal position, and in doing so causes the lug 42 to slide along the cam 71 to give the lock 65 a further right hand motion which will move the release element or inclined surface 72 out of the path of the rod 40.

From the foregoing it will be seen that the invention provides a simple form of lock effective to hold the remover R in its thread pick-up position with the lip 32 low enough to engage the thread of the depleted bobbin. In the preferred form the lock member has a latch or detent 57 which moves over a part 58 of the carrier member 17, while in the modified form

the detent 70 moves over a part of the carrier, namely, the lifting lug 42, to hold the carrier locked in down position. In both forms the resetter effects unlocking of the lock member before it engages the lifting lug 42, and continued upward movement of the resetter to effect return of the carrier to normal position causes the lock to have a still further movement which moves it out of the path of the resetter.

Having thus described the invention it will be seen that changes and modifications of the foregoing specific disclosure may be made without departing from the spirit and scope of the invention.

What is claimed as new is:

1. In a weft replenishing loom having a pneumatic thread remover, a carrier for the thread remover mounted for movement relatively to the loom, means moving the carrier from the normal idle position thereof to a thread pick-up position incident to a weft replenishing operation of the loom, a lock normally in non-locking position with respect to the carrier when the latter is in the idle position thereof but moving to locking position with respect to the carrier when the latter is moved to the thread pick-up position thereof, and a resetter for the carrier having a movement subsequent to said weft replenishing operation and effective during the first part of the movement thereof to move said lock to unlocking position with respect to the carrier and thereafter effective during the latter part of said movement to return said carrier to the normal idle position thereof.

2. In a weft replenishing loom having a bobbin transfferer arm and a pneumatic thread remover, the loom having a stud on which the transfferer arm is pivotally mounted, a carrier member mounted on the stud for pivotal movement relatively thereto and normally in idle position but moved to thread pick-up position by the transfferer arm incident to a weft replenishing operation of the loom, a lock member normally in non-locking position relatively to the carrier when the latter is in the idle position thereof and moving to locking position relatively to the carrier when the latter moves to said thread pick-up position thereof, and resetting means operating subsequent to said weft replenishing operation effective first to move said lock member to unlocking position relatively to the carrier and thereafter move said carrier from said thread pick-up position thereof to the normal position thereof.

3. In a weft replenishing loom having a bobbin transfferer arm and a pneumatic thread remover, a carrier member for the thread remover mounted for movement with respect to the loom, said carrier normally being in idle position and moved to thread pick-up position by the transfferer arm incident to a weft replenishing operation of the loom, a lock member normally in non-locking position with respect to the carrier member when the latter is in the normal position thereof but moving into locking position with respect to the carrier member when the latter moves to the thread pick-up position thereof, a regularly moving resetter effective on a movement thereof subsequent to said weft replenishing operation first to move said lock member to non-locking position relatively to the carrier member and thereafter return the carrier member from the thread pick-up position thereof to said normal idle position thereof, one of said members having a cam engaging the

other member to effect movement of the lock member out of the path of the regularly moving resetter when the latter returns the carrier member to the normal idle position thereof.

5. In a weft replenishing loom having a bobbin transfferer arm and a pneumatic thread remover, a carrier for the thread remover mounted for movement relatively to the loom, said carrier normally being in idle position and moved to thread pick-up position by the transfferer arm incident to a weft replenishing operation of the loom, a lock for the carrier, a pivot on which the lock is angularly movable fixed with respect to the loom, said lock being in non-locking position relatively to the carrier when the latter is in the normal idle position thereof, means moving the lock to locking position with respect to the carrier when the latter moves to the thread pick-up position thereof, and a resetter having a movement subsequent to said weft replenishing operation and effective during the first part of said movement to move the lock around the pivot thereof against the action of said means to non-locking position with respect to the carrier and thereafter return the carrier from the thread pick-up position thereof to the normal idle position thereof.

6. In a weft replenishing loom having a bobbin transfferer arm and a pneumatic thread remover, a carrier for the thread remover mounted on the loom for movement relatively thereto, said carrier normally being in idle position but moved to thread pick-up position by the transfferer arm incident to a weft replenishing operation of the loom, a lock member, a stationary pivotal support for the lock member, the latter having a release finger and a locking finger, the latter finger normally being in non-locking position with respect to the carrier when the latter is in the normal idle position thereof, said locking finger moving into locking position relatively to the carrier when the latter moves to the thread pick-up position thereof, and a resetter operative subsequent to said replenishing operation first to engage said release finger and rock said lock about said pivot to move the locking finger to non-locking position with respect to the carrier, said resetter thereafter effective to return the carrier from the thread pick-up position thereof to the normal idle position thereof.

7. The combination set forth in claim 5 wherein in the carrier is provided with a cam for engagement with said release finger effective as the carrier moves to the idle position thereof to rock said lock in such manner as to move the release finger out of the path of said resetter.

8. In a weft replenishing loom having a bobbin transfferer arm and a pneumatic thread remover, a carrier for the thread remover mounted for vertical movement relative to the loom and normally in raised idle position but moved downwardly by the transfferer arm to thread pick-up position incident to a weft replenishing operation of the loom, a shelf forming part of said carrier, a lock normally in non-locking position with respect to said shelf when the carrier is in the normal idle position thereof but effective to move into locking position with respect to said shelf to prevent movement of the carrier toward the normal position thereof when said carrier is moved to the thread pick-up position thereof, and a carrier resetter below said shelf effective by upward movement thereof subsequent to said 70 weft replenishing operation first to engage and

remove said lock to non-locking position with respect to said shelf and thereafter engage said shelf to raise the carrier from the thread pick-up position thereof to the normal idle position thereof.

8. In a weft replenishing loom having a bobbin transferrer arm and a pneumatic thread remover, a carrier member for the thread remover mounted for movement relatively to the loom, said carrier normally being in idle position but moved to thread pick-up position by the transferrer arm incident to a weft replenishing operation of the loom, a lock member normally in non-locking position relatively to the carrier member when the latter is in the normal idle position thereof, but effective to move into locking position relatively to the carrier to prevent movement of the latter in a direction toward the normal position thereof incident to movement of said carrier to the thread pick-up position, a release element on said lock, and a resetter effective subsequent to said weft replenishing operation first to engage said release element and move said lock member to non-locking position relatively to the carrier member and thereafter engage said carrier member and return the latter from the thread pick-up position thereof to the normal position thereof.

9. In a weft replenishing loom having a bobbin

5
10
15
